UNITED STATES PATENT OFFICE

153,592

DESIGN FOR AN OVEN

William Fader, Newark, N. J.

Application April 3, 1947, Serial No. 138,127

Term of patent 14 years

(CL. D81—26)

To all whom it may concern:

Be it known that I, William Fader, a citizen of the United States, residing in Newark, county of Essex, and State of New Jersey, have invented a new, original, and ornamental Design for an Oven, of which the following is a specification, reference being had to the accompanying drawing, forming part thereof.

In the drawing:

Figure 1 is a top plan view of the oven embodying my new design.

Figure 2 is a front view thereof.

The sides and back of the oven, not shown, are substantially plain.

I claim:

The ornamental design for an oven, as shown and described.

WILLIAM FADER.
